Primary Examiner—Lucy Lieberman(57) **CLAIM**

The ornamental design for a watch, as shown and described.

DESCRIPTION

FIG. 1 is a top perspective view looking in at the right side of a watch showing my new design;

FIG. 2 is a top plan view thereof;

FIG. 3 is a front elevational view with the rear elevational view a mirror image;

FIG. 4 is a right side view thereof; and,

FIG. 5 is a left side view thereof.

The portions of the drawings provided by broken line are intended to reflect environment, and do not form a part of my design.
